UNITED STATES PATENT OFFICE.

JAMES ROGERS, OF CHICAGO, ILLINOIS.

SUNSHADE-SUPPORT.

1,070,068.

Specification of Letters Patent. Patented Aug. 12, 1913.

Application filed October 14, 1912. Serial No. 725,727.

To all whom it may concern:

Be it known that I, JAMES ROGERS, a citizen of the United States, residing at Chicago, in the county of Cook and State of Illinois, have invented certain new and useful improvements in Sunshade-Supports, of which the following is a specification.

The supporting device which is the subject of the present invention is designed 10 more particularly for use in connection with trucks and other vehicles having a shade over the driver's seat.

It is the object of the invention to provide a simple and efficient device of the kind 15 stated which permits ready adjustment of the shade and which will securely lock the same in adjusted position. These objects are attained by a novel combination and arrangement of parts to be hereinafter described and claimed, reference being had to the accompanying drawing in which—

Figure 1 is a side elevation showing the application of the invention; Fig. 2 is an enlarged side elevation of the support; Fig. 3 25 is an edge view thereof; Fig. 4 is a vertical section on the line 4—4 of Fig. 2, and Fig. 5 is an elevation showing the shade folded and swung to hang under the seat.

Referring specifically to the drawing, 10 30 denotes the seat of the vehicle provided with a shade 11 which is carried by bows 12 pivoted on each side to a stem 13 so that the shade may be folded. The stems on each side of the shade are pivotally connected to a support mounted on the corresponding side of the seat, so that the shade may be raised or lowered.

Each support comprises a base member 14 having the usual trunnions 15 at its ends 40 whereby it is mounted in bearings 16 carried by the end of the seat. The base member has a top arcuate slot 17 and an intermediate portion 18 provided with a square transverse aperture 19 having a reduced portion 20. This aperture is below the slot 17, and between said slot and aperture is a series of perforations 21 arranged in a curve which is concentric to the slot.

The stem 13 has at its lower end, on each 50 side, an outstanding pin 23 provided with a head 24. Above the pins 23, the stem has, on each side, a lug 25, and above these lugs,

the stem has an aperture 26 through which is adapted to pass a bolt 27 equipped with a hand-nut 28.

In assembling the parts, one of the pins 23 is passed through the aperture 19 and the stem 13 is then allowed to drop down until the pin seats in the reduced portion 20 of the aperture. This provides a pivotal 60 support for the stem. When the pin is positioned as stated, the lug 25 on the same side thereof is located so that it can enter one of the perforations 21, and the aperture 26 coincides with the slot 17. The bolt 27 65 may now be passed through the aperture and slot, and the nut 28 is screwed on the bolt against the face of the member 14. The slot 17 permits the shade to be lowered and also adjusted to perpendicular or slanting position. The lug 25 assists to hold the parts in adjusted position.

To remove the shade, the bolt 27 is removed and the stem 13 lifted until the head 24 is in line with the aperture 19, after 75 which the stem can be taken off. The aperture 19 is large enough to permit the head 24 to pass therethrough but the reduced portion 20 of said aperture is too narrow to permit the head to pass therethrough. Two 80 pins 23 and lugs 25 are provided in order that the stem 13 may be reversed. The shoulders 29 formed by the reduced portion 20 of the aperture 19 serve to temporarily support the stem 13 while it is being applied 85 or removed.

The device herein described is simple in construction, and efficient in operation. The bow is firmly held, making accidental disengagement impossible, and also eliminating 90 rattling and wear.

The stems 13 are on the outside of the base member 14 in order that the shade may be folded and swung down under the seat as shown in Fig. 5. Figs. 1 and 2 show the 95 support for the shade looking from the inside thereof. In order to place the shade in the position shown in Fig. 5, it will be necessary only to remove the bolt 27.

I claim:

The combination of a base plate having an arcuate slot and an aperture which is provided with a reduced bottom portion, a member having an outstanding pivot pin

provided with a head which is of greater width than the width of the reduced portion of the aperture, said headed pin seating in said reduced portion of the aperture, a bolt 5 carried by the member and passing through the aforesaid slot, and a nut screwed on the bolt.

In testimony whereof I affix my signature in presence of two witnesses.

JAMES ROGERS.
